UNITED STATES PATENT OFFICE.

JAMES H. ANDERSON, OF NEWTON, KANSAS.

GRAIN-BINDER.

SPECIFICATION forming part of Letters Patent No. 295,711, dated March 25, 1884.

Application filed December 19, 1881. (No model.)

To all whom it may concern:

Be it known that I, JAMES H. ANDERSON, of Newton, in the county of Harvey and State of Kansas, have invented certain new and useful Improvements in Grain-Binders, of which the following is a specification.

My invention relates to that class of binders in which the straw is packed against the compressor so constructed as to yield under the pressure of the compacted material when the receptacle becomes filled, such yielding movement being utilized by connecting the parts with the clutching mechanism, so as to make the binding of the grain wholly automatic.

15 My invention may be applied to any machine operating in the manner above described; but having adapted it to the form shown in the patent issued to John F. Appleby, No. 212,420, February 18, 1879, I have shown my 20 device to conform to his Figure 2.

In Fig. 1 I show only such parts as are necessary to make the operation of my invention clear. Fig. 2 is a cross-section of C and B, taken in the line $x-x$.

25 A is the needle, secured to the shaft a and rocking with it.

C is the compressor, forming one side of the gavel-receptacle; and B, the adjustable portion of it.

30 D is the swinging bar, upon which C is pivoted at d' . C is bored through, so as to admit the bar D and permit a rocking motion. e is a lug upon the side of C, provided with a hole for receiving loosely the rounded extremity of E. The bar D is pivoted at d to the heel a' of the needle. The result of this last construction is to cause the compressor to move upward as the needle is thrown forward and down. The lever E is secured to the 35 shaft e , which is connected with the clutch tripping mechanism. (Not shown.)

H is a shaft, upon which two or more cranks, G G', are mounted, the said cranks carrying the packers I.

40 F is a thrust-rod, to which the bar D is pivoted at f , for raising and lowering the compressing and tripping parts, to admit of the discharge of the bundles.

K is the decking onto which the grain is deposited from the harvester.

L is a plate opposing K, and with it forming a chute through which the grain is carried, and forming the upper side of the receptacle M.

The tying mechanism is located above L in 55 the usual manner.

All these details, as well as their operations, (aside from my part B,) are shown and fully described in the patent above referred to.

B is secured to C in any suitable manner 60 that may admit of adjustability. As shown, the part B is provided with a series of holes, and with bolts. It may be moved bodily, or, if wished, it may be thrown forward at bottom or top.

65 It is customary to provide several holes in D, and to vary the position of C on D, for varying the size of the bundle produced; but this has serious objections in practice, which I will now point out.

70 The clutching mechanism is tripped by the rocking of the shaft e , as is shown in the patent above referred to.

The lever E is connected to the compressor by passing loosely through the lug c . If C is made adjustable on the bar D, the leverage on e will vary. If C is moved upward to make a small bundle, the lug c , that moves the lever E, is moved near its fulcrum, and the lever being thus shortened a greater 80 amount of pressure on C will be required to do the tripping. Because of these variations, due to the adjustment of C on the bar, the uncertainties mentioned are produced, and which I avoid by making the size 85 of the receptacle adjustable in the manner shown, thus leaving the leverage on E a constant quantity.

I am aware that it is not new to make the receptacle adjustable in size, and that C has 90 been made to adjust on D, and so do not claim adjustability, broadly; but

I do claim—

1. The combination of the tripping compressor C, formed as described, with the section B, U-shaped in cross-section, and adjust- 95

ably applied to said compressor, substantially as described.

2. The adjustable compressor having the section B, U-shaped in cross-section, the main part of the compressor C entering the part B, the whole combined with the tripping-lever E, the needle A, bar D, passed

through and supporting the compressor, and having pivotal connection to the same, substantially as described.

JAMES H. ANDERSON.
